(57) **CLAIM**

(21) Appl. No.: **29/220,948**

The ornamental design for a combined mop head and retaining clamp, as shown and described.

(22) Filed: **Jan. 7, 2005**

DESCRIPTION

(51) LOC (8) Cl. **04-01**

FIG. 1 shows the front view of the combined mop head and retaining clamp of the present invention.

(52) U.S. Cl. **D32/50**

FIG. 2 shows an elevation view of the combined mop head and retaining clamp of the present invention.

(58) **Field of Classification Search** 32/40,

FIG. 3 shows the opposite elevation view of the combined mop head and retaining clamp of the present invention.

32/44, 50; 15/116.1, 116.2, 119.1, 119.2,

FIG. 4 shows the top view of the combined mop head and retaining clamp of the present invention.

15/147.1, 228, 115, 146, 229.1, 150

FIG. 5 shows the bottom view of the combined mop head and retaining clamp of the present invention; and,

See application file for complete search history.

FIG. 6 shows the rear view of the combined mop head and retaining clamp of the present invention.
